UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

SEMI-AUTOMATIC TELEPHONE SYSTEM.

1,232,345.

Specification of Letters Patent.

Patented July 3, 1917.

Application filed September 7, 1915. Serial No. 49,238.

To all whom it may concern:

Be it known that I, ALBEN E. LUNDELL, a citizen of the United States, residing at New York, in the county of Bronx and State of New York, have invented certain new and useful Improvements in Semi-Automatic Telephone Systems, of which the following is a full, clear, concise, and exact description.

10 This invention relates to telephone systems, and particularly to semi-automatic telephone exchange systems.

It has been the practice, in the operation of semi-automatic telephone exchanges, for 15 the operator to write a memorandum on all calls to show the number of the called subscriber. The writing of this memorandum introduces a considerable drag on the operator, and in addition, is the cause of ringing 20 many wrong numbers, it being found that the operator usually attempts to depress the numerical keys with a pencil in her hand, which practice results in the depression of the wrong key. An object of the invention, 25 therefore, is the provision of means whereby the necessity of the operator making a memorandum of the called line is avoided. To this end a circuit arrangement is provided whereby the sender apparatus remains 30 attached to the cord circuit until a certain interval of time after the response of the called subscriber, and additional means are provided so that, up to the time of the release of the sender, the operator can determine 35 the register setting on the associated connection.

In the operation of semi-automatic telephone exchanges having party lines incorporated therein, considerable trouble has 40 been experienced when one party on a line calls another party on the same line, by having the called party test busy, with the consequent loss of a call. Another object of this invention relates, therefore, to an improved method of handling revertive calls in a semi-automatic telephone system.

Briefly, the operation of the system is as follows: A subscriber "S" wishing to talk with another subscriber "T" removes his receiver from the switch hook to light a lamp at the central station. The operator, observing the lamp, inserts a plug of a cord circuit into the jack corresponding to the lamp,

thus placing herself in communication with the calling subscriber, from whom she learns 55 the number of the wanted subscriber. She then depresses the numerical keys, corresponding to the number of the wanted subscriber, to control switches which hunt for the terminals of the wanted line. The reg- 60 isters, connected with the numerical keys, are so arranged that they are held in their set position until the called subscriber answers. Connected to the register is an indicating device on which the number of the 65 called subscriber is displayed, by lamps or in any convenient manner, in the listening-in position of the listening sequence switch. Also, and until the called subscriber answers, the operator may, after the listening 70 sequence switch has passed out of listening-in position, depress a listening key to move the listening sequence switch out of any position it may occupy at that instant, into listening-in position, to again display the 75 number of the called subscriber on the indicating device. The ability to do this obviates the necessity of writing a memorandum of the called party's number.

Should the call be a revertive one, the 80 called line will naturally test busy. To determine whether or not this is a revertive call, the operator depresses her listening key sending the listening sequence switch into listening position, and displaying the 85 number of the called party on the indicating device. She then compares the number of the called line with the number of the jack of the calling line, and, if the call is a revertive one, she asks the calling party to 90 hang up his receiver for a moment, until she rings the called party. The calling party, after a short interval of time, again removes his receiver from the switch hook, and, the called subscriber having been rung, 95 the calling and called subscribers are telephonically connected.

Figures 1, 2 and 3 taken together, with Fig. 2 below Fig. 1 and Fig. 3 to the right of Fig. 2, illustrate diagrammatically a telephone system embodying this invention with enough of the telephone system shown to illustrate an application of the invention thereto. For a complete exposition of a telephone system to which this invention 100 may be applied, reference may be had to

Patent No. 1,168,318 granted to A. E. Lundell, January 18, 1916, or to Patent No. 1,125,573 granted to F. R. McBerty January 19, 1915.

5 A subscriber S, wishing to converse with another subscriber T, removes his receiver from the switch hook closing the circuit through the line relay 100, which attracts its armature, causing the lighting of the line lamp 101. The operator, observing the lamp 101 lighted, inserts a plug 102 of a cord circuit into the jack 103 associated with the line lamp 101. The insertion of plug 102 closes a circuit from battery, relay 117, 10 sleeve of the plug 102, sleeve of the jack 103, cut-off relay 104, and thence to ground, thus causing the energization of relay 117 and cut-off relay 104 which attracts its armatures causing the deenergization of the line relay 100 and the consequent extinguishing of the line lamp 101.

15 The energization of relay 117 closes a circuit from battery through the motor magnet of sequence switch 105, sequence switch contact 118, contact and left-hand armature of relay 117, and thence to ground. Sequence switch 105 moves from the first to ~~the~~ second position.

20 The energization of relay 117 ~~also~~ closes a circuit from battery through the ~~motor~~ magnet of sequence switch 107, contact 119 of sequence switch 107, contact and right-hand armature of relay 117, and thence to ground. Sequence switch 107 moves from 25 position one to position seven.

25 The passing of the sequence switch 105 from the first to the second position, and of sequence switch 107 from the first to the seventh position, closes a circuit from battery, through relay 210, contacts 211 of sequence switch 200, contact 120 of sequence switch 107, contact 121 of sequence switch 105, and thence to ground, causing the energization of relay 210. This in turn closes a 30 circuit from battery, motor magnet of sequence switch 200, contact 212 of sequence switch 200, contact and armature of relay 210, and thence to ground, starting the sequence switch 200 of the cord finder in 35 search of the cord taken for use in a manner well known and disclosed in the above mentioned Patent No. 1,168,319.

40 The operator, being now in communication with the calling subscriber, ascertains the number of the wanted line and depresses number keys corresponding to the number of the called line, which keys close the corresponding contacts A, B, C of the district brush and district group registers and contacts 300, 301, 302, 303, of the thousands, hundreds, tens and units registers respectively, and should the called party be located on a party line, contact 304 of the station's register is closed. The bank of numerical 45 keys above referred to, and the manner in

which the register contacts are closed is not shown or illustrated herein, and for a complete description thereof reference is had to the above cited patents.

Attached to the registers is an indicating device 315 containing a plurality of sections corresponding to the thousands, hundreds, tens and units, the station, the district and the group of lines in the exchange.

50 Referring to Fig. 3, it will be seen that the thousands, hundreds, tens and units groups each contain ten indicating devices, such as lamps, which may be selectively operated in accordance with the number of the called line set up on the register.

55 We will assume that the number of the called line is 5487, that the district brush corresponding to this station is represented by A and B, and that the district group is represented by C. In the call first to be described we will assume that the calling subscriber is on a straight line, that is, as distinguished from a party line, but when describing a reverting call we will assume that the calling party is the third party on the line and, therefore, the station's register will be represented by the digit 3 in the proper section of the indicating device 315.

60 Located at the cord finder are indicating control relays 201, 202 and 203 which control, at their various armatures, break points in the operating circuits for the various banks of signals shown in the indicating device 315, and in the listening-in position (position 7) of the listening key sequence switch 107 a circuit is completed from battery through the relays 201, 202 and 203 in series from battery, conductors 204, 205, sequence switch contact 108, to ground, energizing said relays and causing the number of the called line to be visually displayed on the indicating device 315 after the called party's number has been set up in the usual manner. As listening sequence switch 107 moves out of its seventh position, relays 201, 202, 203 are deenergized, obliterating the indication of the called line, and we will assume that the call progresses in the usual manner; that is, the called subscriber is not using his apparatus and, therefore, his line is found idle 65 on test, ringing takes place and subscriber S is placed in telephonic communication with subscriber T.

70 If during the progress of the call, and until the called subscriber answers, it is necessary, for any reason, for the operator to ascertain the number of said called subscriber, the number of the called line on the indicating device having been obliterated because of the listening sequence switch 107 passing out of its seventh position, the operator depresses listening key 109, closing an energizing circuit for the motor magnet of listening sequence switch 107, from battery, motor magnet of sequence switch 107, con-

tacts 116 of said sequence switch, contacts of switch 109, and thence to ground. Sequence switch 107 thereupon moves back to normal where it is caused to continue on to position seven, through being energized over the circuit as previously traced. In the listening-in position, (7), circuit is again completed for the indicating control relays 201, 202, 203 in series, placing ground at the various armatures of said relays from the battery connected with the indicating device 315, and again displaying the number of the called subscriber on the indicator 315.

As the final sequence switch moves into its sixteenth and talking position on a successful call, a circuit is completed from battery, one winding of the repeating coil 110, supervisory relay 111, out over the line of the called subscriber and back through another winding of the repeating coil 110 to ground, energizing the supervisory relay 111 and completing a circuit from battery, lower right contact of sequence switch contact 112, armature and front contact of supervisory relay 111, conductor 113, upper right contact of sequence switch contact 114, conductor 209, time release relay 206 to ground at the interrupting device 207.

When the interrupting device 207 closes this circuit, the time release relay 206 will be energized, attracting its armature and completing a locking circuit for itself at its inner armature, maintaining itself energized irrespective of what happens at the interrupting device 207. When the interrupting device 208 closes its circuit, it will place a ground at the outer armature and front contact of the time release relay 206 to move sequence switch 200 of the cord finder out of its sixteenth and into its seventeenth position, from which position it will be disconnected from the cord circuit taken for use and returned to normal in the usual manner.

If the called subscriber's line tests busy, the final sequence switch moves into the seventeenth position, completing a circuit from battery, one winding of the repeating coil 110. Supervisory relay 111 to ground at the interrupting device 113, and a busy signal will be transmitted back to the calling subscriber. Under these conditions the time release relay 206 will be intermittently energized. However, the relation of the interrupters 207 and 208, which are rigidly connected to the same rotating shaft, is such that, while the circuit is completed through 207 and the relay 206 is energized, the circuit through 208 is broken, and while the circuit through 208 is established, that through 207 is broken, and therefore the motor magnet of sequence switch 200 does not receive the energy to move it out of the sixteenth position. The cord finder, therefore, remains connected to the cord circuit

until after the operator removes the plug 102 from the jack 108, when it is disconnected in a manner well known in the art.

What is claimed is:

1. In a telephone system, a plurality of telephone lines, a connecting circuit for interconnecting said lines, an indicating device therefor, a register for registering the number of the called line, said indicating device operating in accordance with the number set up on the register, and means under the control of the operator, at any time after the call has progressed beyond the position where the called number was first displayed on said indicating device, for displaying said number on said indicating device.

2. In a telephone system, a plurality of telephone lines, connecting circuits for interconnecting said lines, an indicating device common to a plurality of said connecting circuits, a register for recording the number of the called line, said indicating device operating in accordance with the number set up on the register, and a key under the control of the operator, at any time after the call has progressed beyond the position where the called number was first displayed on said indicating device, for displaying said number on said indicating device.

3. In a telephone system, a plurality of telephone lines, a connecting circuit for interconnecting said lines, a multi-position automatic switch and an indicating device for said circuit, a register, said indicating device operating in accordance with the number set up on the register for displaying said number only when said switch is in a predetermined position, and means under the control of the operator for returning the said switch to the predetermined position.

4. In a telephone system, a plurality of telephone lines, connecting circuits for interconnecting said lines, multi-position automatic switches individual to said connecting circuits, an indicating device and a register, said indicating device operating in accordance with the number set up on said register for displaying said number when the switch for a connecting circuit taken for use is in a predetermined position, and means under the control of the operator for returning said switch to said predetermined position after said switch has progressed to an advanced position.

5. In a telephone system, a plurality of telephone lines, connecting circuits for interconnecting said lines, multi-position automatic switches individual to said connecting circuits, an indicating device and a register, said indicating device operating in accordance with the number set up on said register for displaying said number when the switch

- for a connecting circuit taken for use is in a predetermined position, and means under the control of the operator for returning said switch to the predetermined position.
- 5 6. In a telephone system, a plurality of telephone lines, a connecting circuit for interconnecting said lines, a multi-position automatic switch for said connecting circuit, an indicating device and a register adapted 10 to be temporarily attached to said connecting circuit, said indicating device operating in accordance with the number of the called line on the register for displaying said number only when said switch is in a predetermined position, means under the control of the operator for returning the said switch to the predetermined position whereby the number of the called line may be again displayed on the indicator.
- 15 7. In a telephone system, a plurality of telephone lines, a connecting circuit for connection thereto, a multi-position automatic switch for said connecting circuit, an indicating device for indicating visually the 20 number of the called line only when said switch is in a predetermined position, and means under the control of the operator for returning said switch to the predetermined position, whereby the number of the called
- line may be again displayed on the indicator.
8. In a telephone system, a plurality of telephone lines, connecting circuits for interconnecting said lines, an operating switch for each connecting circuit, an indicating device and a register, a cord finder common to a plurality of said connecting circuits for placing said register and said indicating device under the control of the connecting circuit taken for use, a sending device under the control of said register operating to control selecting switches for searching for the line corresponding to the number on said register, operating circuits for said indicating device, means at said cord finder for closing break points in said operating circuits, means, under the control of the operating switch of the connecting circuit taken for use, operating to control the circuit controlling means of said indicating means, when 40 said operating switch is in a predetermined position, and a key under the control of the operator for returning, at will, said operating switch to the predetermined position.
- 45
- 50
- 55
- In witness whereof, I hereunto subscribe my name this 3rd day of September A. D., 1915.

ALBEN E. LUNDELL.
